SMOKING PIPE OR HOLDER

Fred L. Warnke, Hartford, Conn.

Application November 21, 1931, Serial No. 576,555

10 Claims. (Cl. 131—12)

This invention relates to smoking pipes, holders for cigars and cigarettes, and in particular to a pipe or holder having means for preventing moisture and liquid forming in the lower portions of the tobacco cavity of the pipe or in the mouth piece, and for preventing any moisture or liquids formed during smoking from entering the mouth of the user.

A primary object of the present invention is to provide an improved form of nicotine retaining receptacle within the pipe stem or holder between the tobacco cavity and the mouth piece end of the stem, this receptacle serving to entrap the condensed liquids and retain them therein until they may be emptied therefrom.

A feature of importance of the invention is that the member within which the nicotine cavity is formed is of the material from which the mouth piece is made, usually hard rubber or bakelite, and preferably is formed therein during the moulding or otherwise making of the stem; so made it does not add appreciably to the weight or size of the stem, and provides means which may be readily kept clean and from which the liquids may easily be emptied.

Another object of the invention is to provide a receptacle preferably formed within the stem of a smoking pipe so that appreciable quantities of liquids accumulating therein during smoking will be retained therein and prevented from entering either the bowl or the mouth of the user with the pipe held in any position.

Another feature of advantage is that tubular projections enter the receptacle or cavity extending from the bowl and from the mouth piece end of the stem so that liquid may accumulate within either end of the receptacle without danger of its entering the bowl or the mouth of the user.

A still further object of the invention is to provide improved connecting means between the bowl and stem of a pipe which may easily be adjusted to properly align the mouth piece end of the stem with the bowl. An important advantage of this connecting means is that a flange employed between the bowl and mouth piece enables adjustments to be readily made to adjust the bowl and mouth piece angularly or rotatably, this flange having its peripheral edge curved and adapted to extend slightly beyond the surface of the bowl extension and mouth piece to present an attractive appearance, to be readily grasped to adjust the connection, and eliminate the necessity of accurate alignment of the contiguous surfaces of the bowl extension and mouth piece.

And finally it is an object of the invention to provide a small air vent in the form of a tube leading into the liquid retaining cavity within the mouth piece through which the smoke passes.

so that the stream of smoke as it enters the condensing receptacle or cavity may come into contact with a small amount of air, thus by intimately mixing with the smoke serving to cool it and aid in condensing the moisture carried by the smoke before entering the mouth piece.

With the above and other objects in view my invention includes the features of construction and operation set forth in the following specification and illustrated in the accompanying drawing.

In the accompanying drawing annexed hereto and forming a part of this specification, I have shown my invention embodied in a smoking pipe and in a cigarette smoking tube or holder of conventional straight form, but it will be understood that the invention can be otherwise embodied and that the drawing is not to be construed as defining or limiting the scope of the invention, the claims appended to this specification being relied upon for that purpose.

In the drawing:

Figure 1 is a longitudinal view in section of a complete pipe made according to the present invention;

Fig. 2 is a cross sectional view taken on the plane of line 2—2 of Fig. 1.

Fig. 3 is a view similar to Fig. 2 showing the form of connection for a different design of stem and mouth piece.

Fig. 4 are perspective views slightly separated of a sleeve and flange forming parts of the connecting means for the bowl and mouth piece of the pipe shown in Fig. 1.

Fig. 5 is an isometric view of the connecting piece between the bowl and stem of the pipe shown in Fig. 1, and

Fig. 6 is a longitudinal section of a cigarette smoking tube or holder having some of the features of the present invention applied thereto.

In the above mentioned drawing I have shown embodiments of the invention which are now deemed preferable, but it is to be understood that changes and modifications may be made within the scope of the appended claims without departing from the spirit of the invention.

My invention in its broadest aspect may include parts adapted to fit within a conventional form of smoking pipe or holder, the shank or extension from the bowl of which is suitably threaded for a connecting piece of novel form. This connecting piece when in place serves to retain a threaded sleeve thereon, the position of which may be varied rotatively and retained firmly in any desired angular position by the connecting piece. Adapted to connect with the threaded sleeve is the internally threaded portion of a hollow receptacle or cavity within the pipe stem and forming a condensation chamber for vapors and moisture contained in the smoke as it comes from the bowl of

the pipe. Into this receptacle may be admitted a limited amount of air in a manner permitting the air to mingle intimately and uniformly with the stream of smoke at its point of admission to the receptacle.

Referring more in detail to the figures of the drawing, and first to Figs. 1 to 5, I provide a pipe bowl 10 having a stem extension 11 provided with a hole 12 entering the tobacco cavity 13 of the bowl 10 at substantially its lowermost point. The outer end of the hole 12 is threaded as shown clearly in Fig. 1 and engages the threaded portion of a connecting piece 14 having a longitudinal opening extending therethrough. A head portion 15 is formed thereon and extended portions 16 of small tubular form project from opposite ends of the member. The inwardly extending end of the hollow connecting piece 14 is threaded to enter the threaded portion of the hole 12 and the extension 16 at this end preferably extends to the cavity 13 of the bowl 10. From the above it will be seen that a passage from the tobacco cavity 13 within the bowl 10 is provided for the smoke within the connecting piece 14, this passage extending to a point within the bowl extension 11 and beyond the head 15 of the connecting piece 14 where the stem or mouth piece is attached.

Adapted to surround the connecting piece 14 and be retained in place by forcing the head 15 against its outer end is a sleeve 17. This sleeve is threaded upon its outer surface and slidably fits over the threaded portion of the connecting piece 14. In the embodiment illustrated the sleeve 17 has a flange 18 closely attached to one end and positioned against the outer surface of the bowl extension 11. This flange 18 may have its hole broached with opposed recesses into which projections 18^a formed on the sleeve 17 may enter.

The outer periphery of the flange 18, shown as circular in Figs. 1 and 2, but which may be of other shapes as indicated in Fig. 3, is rounded or curved as shown in Figs. 1 and 4. The diameter of this flange is slightly greater than the diameters of the bowl extension and the mouth piece so that the flange attached to the sleeve 17 by means of the projections 18^a may be easily grasped to rotate sleeve 17 in aligning the mouth piece with the bowl. By reason of the periphery of the flange being curved in cross section, slight inaccuracies of alignment of the abutting surfaces of the bowl extension 11 and the stem are concealed and are not apparent.

Adapted to threadedly engage the sleeve 17 is the stem or mouth piece 19 within which is formed a cavity 20. Internal threads on an annular member 21 at the open end of the cavity 20 engage the threads on the connecting sleeve 17. The opposite end of cavity 20 terminates within the stem 19, through which extends a smoke passage 24.

The cavity forming the smoke receptacle 20 and the annular member 21 are formed during the moulding of the stem 19 which is usually of bakelite, rubber or other moldable product so that the member 21 may be retained rigidly in position therein. Preferably the outer surface of member 21 is roughened to aid in retaining it in molded position. Within the inner end of the cavity 20 is placed a small tube 23 extending partly within the cavity 20 and partly extending therefrom into the mouth piece portion of the stem 19 so that it may be embedded within and retained in position by the material of the stem. The passage 24 joins the opening within the tube 23 to form a continu-

ous passage from the space within the cavity 20 through the mouth piece 19.

Extending transversely through the stem 19 and into the condensing chamber or cavity 20 is a short tube 25 having a small opening or orifice therethrough so that small quantities of fresh air may be admitted to the cavity 20 simultaneously with the admission of smoke during use of the pipe. This addition of a small quantity of air to the smoke at a point within the cavity or receptacle 20 closely adjacent the end of extension 16 and just as it is drawn from the bowl 10 not only serves to cool it appreciably but also condenses some of the contents of the smoke. The air admitted through tube 25 mingles uniformly with the smoke within the cavity 20 and for that purpose the inner ends of projection 16 and tube 25 are closely adjacent, the end of tube 25 being at the center of the stream of smoke as it enters the cavity.

The operation of the parts above described will be for the most part obvious but a brief outline will be given.

To assemble the parts, the connecting piece 14 with the threaded sleeve 17 thereon is screwed into the bowl extension 11, the flattened sides 23 of the head portion 15 of this connecting piece enabling a wrench or other tool to be conveniently used. The stem 19 with the annular internal threaded member 21 molded therein is then screwed on to the threads on the sleeve 17. With the tubular extensions 16 and 23 formed on the connecting piece 14 and on the stem 19 disposed as shown in the drawing, a relatively large amount of condensate from the smoke may be retained within the cavity or receptacle 20 in the pipe without danger of its entering the mouth of the user or passing back into the pipe bowl cavity 13. In any position of the pipe any condensate formed and entrapped within the cavity 20 will not so completely fit the cavity that it will enter either of the tubular extensions 16 or 23 and run either toward the mouth piece end of the stem 19 or back into the pipe bowl. When the pipe has been completely smoked the stem 19 may be unscrewed from the connecting member 14 and the cavity completely emptied and dried of its contents.

The bowl extension 11 and stem 19 may be correctly and readily aligned to position the mouth piece end of the stem 19 angularly with relation to the bowl by loosening the connecting piece 14, rotating the sleeve 17 a portion of a turn. After tightening the connecting piece 14 with the sleeve 17 clamped in a new rotative position, the stem 19 may be again threaded on the sleeve 17. In this manner the sleeve 17 may be adjusted to a position so that the periphery of the bowl extension 11 and the stem 19 are in proper angular relationship. The flange 18 being interposed between them and extending beyond the diameters of the bowl extension 11 and stem 19 enables the adjustments of the sleeve 17 to be easily made.

In Fig. 6 of the drawing there is shown a cigarette holder having some of the features of the present invention applied thereto. Within the cigarette holding end of the tubular member 30 is an annular member 31. The outer surface of this member 31 may be roughened or so formed that it will be securely retained within the tube. Preferably this member 31 is of metal such as duralumin and may be molded within the tube. The inner surface of this member 31 may be shaped to retain a cigar or cigarette.

The portion of the holder adjacent the member 31 is recessed as shown at 32 forming a condensing chamber or cavity similar to that shown at 20 in Fig. 1. From the inner end of this cavity 32 is 5 a passage 33 extending to the mouth end of the tube.

Extending laterally into the tube 30 from a point closely adjacent the inner end of member 31 is a small tube 34, preferably of metal. Through 10 this tube 34 a small amount of air may be admitted. The position of the inner end of this tube 34 is such with relation to the member 31 that the air mingles intimately with the smoke at the point wherein both smoke and air enter the cavity 32. 15 To aid in this mixing of the smoke and air the tube 34 is extended to a point substantially at the axis of the holder so that the air is admitted to the center of the stream of smoke as it enters the cavity 32.

20 The functions of this cavity 32 and the tube 34 are similar to the corresponding parts in Fig. 1 in aiding the condensation of liquids within the smoke by promptly cooling it and allowing the condensed elements to be retained within the cavity. As the annular member 31 is of metal 25 and as the cigarette contacts with this metallic member exclusively, the cigarette may be entirely consumed without danger of burning the holder. When consumed the ashes remaining in the 30 holder may be blown out.

What I claim is:

1. A smoking pipe comprising in combination, a bowl having an extension formed thereon, a connecting piece inserted within said extension, a 35 threaded sleeve adapted to be secured in adjustable rotative position on said connecting piece, a stem disposed adjacent said extension and having a threaded portion engaging the threads on said sleeve whereby said stem is held in position 40 thereon, and a conduit through said extension, connecting piece and stem.

2. A smoking pipe comprising in combination, a bowl having an extension formed thereon, a connecting piece inserted within said extension, a 45 threaded sleeve adapted to be secured in adjustable rotative position on said connecting piece, a flange connected to said sleeve and disposed between said sleeve and extension, a stem abutting against the flange and having a threaded portion 50 engaging the threads on said sleeve whereby said stem is held in position thereon; and a conduit through said extension, connecting piece and stem.

3. A smoking pipe comprising in combination, 55 a bowl having an extension formed thereon, a connecting piece inserted within said extension, a threaded sleeve adapted to be secured in adjustable rotative position on said connecting piece, a flange connected to said sleeve and disposed 60 between said sleeve and extension, the outer edge of said flange being rounded and extending slightly beyond the surface of the extension, a stem abutting against the flange and having a threaded portion engaging the threads on said 65 sleeve whereby said stem is held in position thereon, and a conduit through said extension, connecting piece and stem.

4. A smoking pipe comprising in combination, 70 a bowl having an extension formed thereon, a connecting piece threaded into said extension, a threaded sleeve loosely fitting over said connecting piece and adapted to be clamped in adjusted 75 rotative position, a flange secured to said sleeve and serving to adjust said sleeve, a stem threaded upon said sleeve and against said flange and ex-

tension, said flange having its outer edge extending beyond the surfaces of said extension and stem and rounded to join the acute edges of said extension and stem, and a conduit through 5 said extension, connecting piece and stem.

5. A smoking pipe comprising in combination, a bowl having an extension formed thereon, a connecting piece inserted within said extension, a threaded sleeve adapted to be secured in adjustable rotative position on said connecting piece, a 10 stem disposed adjacent said extension and having a threaded portion engaging the threads on said sleeve, said stem having an enlarged cavity therein, and an extension on said connecting piece 15 extending into said cavity.

6. A smoking pipe comprising in combination, a bowl having an extension formed thereon, a connecting piece inserted within said extension, a threaded sleeve adapted to be secured in adjustable rotative position on said connecting piece, a stem disposed adjacent said extension and having a threaded portion engaging the threads on said sleeve, said stem having an enlarged cavity therein and a transverse tube 20 through the wall of said stem entering said cavity 25 and extending substantially to the central axis thereof, and an extension on said connecting piece extending axially into said cavity adjacent said tube whereby smoke entering the cavity 30 through said extension will mingle intimately with air entering the cavity through said tube.

7. A smoking pipe comprising in combination, a bowl having an extension formed thereon, a connecting piece inserted within said extension, a flange on said connecting piece abutting against the outer end of said extension, a stem having an enlarged cavity at its outer end abutting against 35 said flange, and means on said connecting piece 40 engaging and securing said stem to said extension in any rotative position.

8. A smoking pipe comprising in combination, a bowl having an extension formed thereon, a connecting piece inserted within said extension, a flange on said connecting piece abutting against the outer end of said extension, a stem having an 45 enlarged cavity at its outer end abutting against said flange and having an annular member inserted within its outer end, and means on said connecting piece engaging said annular member and securing said stem to said extension in any 50 rotative position.

9. A smoking pipe comprising in combination, a bowl having a bowl extension, a stem disposed in alignment with said bowl extension, a hollow 55 connecting piece threaded into said bowl extension and extending into said stem, a flange mounted on said connecting piece and disposed between adjacent ends of said extension and stem, and a metal insert within the end of said stem engaging an extended portion of said connecting piece whereby said connecting piece may engage said insert and secure the stem to the extension in any rotative position.

10. A smoking pipe comprising in combination, 65 a bowl having a bowl extension, a stem disposed in alignment with said bowl extension, a hollow connecting piece extending into said bowl extension and having a sleeve thereon extending into said stem, and a metal insert within the end of said 70 stem whereby the sleeve on said connecting piece may engage said insert and secure the stem to the extension in any rotative position.
